UNITED STATES PATENT OFFICE

MATTHEW F. KEESE, OF SOUTH MILWAUKEE, AND ALLAN R. TAYLOR, OF MILWAUKEE, WISCONSIN, ASSIGNEES TO BUCYRUS-ERIE COMPANY, OF SOUTH MILWAUKEE, WISCONSIN, A CORPORATION OF DELAWARE

HYDRAULIC DREDGE

Application filed December 20, 1928. Serial No. 155,928.

This invention pertains to that type of floating dredge which carries, pivoted at the bow, a ladder, so-called, which is to be lowered into the water at an angle of about 45 degrees from the horizontal. The ladder carries a cutter-head for stirring up the material to be excavated, a shaft for driving the cutter-head, and a suction pipe for pumping up the excavated material.

10 This pipe must necessarily have a pivoted joint at the point where it leaves the ladder and enters the hull of the dredge; and this joint presents a problem which we believe we are the first to solve with complete satisfaction.

15 The two most common solutions of the past are as follows:

(a) The pipe makes a right angle turn at the axis of the trunnions which hold the ladder to the hull, passes along the axis of the trunnions, then turns again at a right-angle and enters the hull. There is a swivel joint in that portion of the pipe which passes along the axis of the trunnions.

20 (b) The pipe bends once, in a ball-and-socket joint at the trunnions.

25 Each of these solutions is open to the objection of having a too sharp bend in the pipe, which impedes the flow of the excavated material.

30 It is the object of our invention to remove this objection, by providing two ball-and-socket joints, so contrived that the total bend will be apportioned substantially equally over the two joints.

35 We are aware that double ball joints are old in the art, but we know of none wherein this purpose is accomplished.

40 Other advantages of our invention will be evident to those skilled in the art, and therefore need not be herein more specifically set forth.

45 Our invention consists in the novel parts, and in the combinations and arrangements thereof, which are defined in the appended claims; and of which one embodiment is exemplified in the accompanying drawings, which are hereinafter particularly described and explained.

Figure 1 is a vertical section of our device, with the digging ladder horizontal.

Figure 2 is a vertical section, with the digging ladder in its mid position.

Figure 3 is a vertical section, with the ladder lowered to its extreme position, 45 degrees from the horizontal.

Figure 4 is a vertical section showing the principle of our invention extended to a quadruple joint.

The hull is shown at 1, with the digging ladder 2 and the trunnion joint 3 between them. These three elements are shown merely conventionally, as they may be of any convenient design, and form no part of our invention. The shaft to the cutter-head is, for a like reason, not shown.

A pipe 4 is rigidly carried by the ladder 2, and a pipe 5 is slidably carried by the ladder. Connecting these two pipes is a sliding joint 6, preferably located in a position which will be under water during digging, so as to eliminate the need of packing the joint. Pipe 4 may be rigidly secured to the ladder 2 in any convenient manner, as by pieces of metal 12, bolted or screwed to the ladder 2 and the joint 6; also by other similar pieces of metal (not shown) secured elsewhere to the ladder 2 and pipe 4. The pipe 5 is held by the ladder 2 and constrained against lateral movement

70 with respect thereto, by the joint 6, which may be augmented, if desired, by other means, such as pieces of metal 13 bolted or screwed to the ladder 2 and bearing against the pipe 5. If desired, the pipe can be built integral, and the ladder jointed.

75 The upper end of the pipe 5 terminates in the male member 7 of a ball-and-socket joint. The female member 8 of this joint is formed integral with the male member 9 of another similar joint.

80 The female member 10 of this second joint is the lower end of a pipe 11, leading into the hull 1 at an angle of 22½ degrees from the horizontal.

85 To simplify the explanation of our device, we have inserted capital letters at certain very important points of the drawings. These letters are to be taken as designations of certain lines perpendicular to the plane of

55

100

the drawing if the ladder is constrained to remain in one vertical plane; or as designations of certain points in the plane of the drawing if the ladder is not constrained to remain in one vertical plane.

5 Thus, if the ladder 2 is pivoted to the hull so as to turn only about a horizontal axis, then a horizontal line through B, perpendicular to the plane of the drawing, represents this axis. If, however, the ladder be swung 10 on a gimbal joint, then B is the point at the intersection of the axes of the two axles of the gimbal trunnions.

According as the ladder is pivoted to the hull to turn about a horizontal line or about a point, so also will the two ball-and-socket joints be thereby constrained to turn about horizontal axes through A and C, or to turn about points A and C. A is therefore the center of the coacting spherical surfaces of the ball-and-socket joint composed of 9 and 10; and C is the center of the coacting spherical surfaces of the ball-and-socket joint composed of 7 and 8.

25 D is a horizontal line, or point, fixed with respect to the ladder 2, but not with respect to the ball-and-socket joint 7, 8. This line, or point, D, coincides with C when the ladder is in its mid position, as shown in Figure 2.

30 Our invention resides principally in the relative location of A, B, and C. We shall first consider them as horizontal lines, passing perpendicularly to the plane of the drawing.

35 Lines A and B are both fixed with respect to the hull 1, and are parallel. They lie at any convenient distance apart, and have the plane joining them depressed at an angle of 22½ degrees from the horizontal.

40 The device is so proportioned and arranged that, when the ladder occupies its mid position, as shown in Figure 2, the line C—and D, which is then, and only then, coincident with C—lies in the same plane as A and B, and is just as far from B as B is from A.

45 If the ladder is raised or lowered from its mid position, then since the line C is held at a fixed distance from the line A by reason of both being fixed in the dumb-bell shaped member 8, 9, the line C will describe a cylinder about the line A as an axis, the radius being the distance AC; and since the line D is held at a fixed distance from the line B by reason of both being fixed in the ladder, the line D will describe a cylinder about the line B as an axis, the radius being the distance BD, which distance is the same as BC of Figure 2, and is equal to the distance AB.

50 The distances AC and BD, being both invariable distances, used as radii about invariable centers, A and B respectively, it is evident that, on moving the ladder in either direction away from its mid position, the line D will cease to coincide with the line C, and

that the departure from coincidence will increase as the ladder departs further from its mid position. This is what necessitates the slippage between the pipe 5 and the pipe 4, at the joint 6.

55 It might be thought that this slippage will cause an appreciable departure from the equal distribution of the angle of rotation of the ladder over the two ball-and-socket joints, but this departure is inappreciable.

60 In Figure 1, in which the ladder has been rotated through 22½ degrees from its mean position, the angle of rotation of the right hand ball-joint exceeds that of the left hand ball-joint by only 22½°—2 arcs in $1/2 \sin 22\frac{1}{2}^\circ$, which is almost exactly 26½ minutes of arc. This renders the slippage at the joint 6 less than 2 per cent of the distance AC between the centers of the ball joints; hence it will be seen that the slippage has been greatly exaggerated in the drawings.

65 Let us now consider that the ladder rotates about a gimbal joint which has its center at the point B, instead of rotating about a horizontal axis through B. The movement of the ladder will now not be limited to a vertical plane.

70 Points A and B are fixed with respect to the hull, A being also fixed with respect to the dumb-bell shaped member 8, 9. A and B lie at any convenient distance apart, with the line joining them depressed at an angle of 22.5 degrees from the horizontal, and extending straight ahead from the dredge.

75 The device is so proportioned and arranged that, when the ladder is in its mid position, the point C—and D, which is then, and only then, coincident with C—lies in the same straight line as A and B, and just as far from B as B is from A.

80 If the ladder is raised or lowered from its mid position, or swung to one side or the other, or if any combination of these motions is made, then since C is held at a fixed distance from A by reason of both being fixed in the dumb-bell shaped member 8, 9, the point C will always remain on the surface of a sphere whose center is at the fixed point A, and whose radius is the fixed distance AC.

85 Similarly, since both the points B and D are fixed with respect to the ladder, B being in addition fixed with respect to the hull, it follows that D must remain on the surface of a sphere whose center is the fixed point B, and whose radius is the fixed distance BD,

90 which distance is the same as BC of Figure 2 and is equal to the distance AB. The distances AC and BD, being both invariable, and used as radii about invariable centers, A and B respectively, it is evident that, on moving the ladder in any direction away from its mid position, the point D will cease to coincide with the point C, and that the departure from coincidence increases as the angle of

95 departure of the ladder from its mean position increases.

tion increases. This small distance, CD, is, as before, taken up by the slip-joint 6.

Since the dumb-bell shaped member 8, 9, is constrained against motion only by the coaction of its spherical surfaces with the spherical surfaces of members 7 and 10, it is evident that this member 8, 9, will readily accommodate itself to any deflection of the ladder that is possible with the particular method of connecting the ladder to the hull.

It is to be understood that the angles, 45 degrees and 22½ degrees, are merely illustrative, and that our invention is equally applicable to any other range of swing and its corresponding mid position.

It is to be understood that the male-female relation of either ball-and-socket joint, or of both joints, may be reversed, though the arrangement shown is the preferred one.

A simple and obvious extension of our principles is shown in Figure 4, in which 1 is the hull and 2 the ladder as in the other drawings. Rigidly attached to the hull is the ladder-section 14 to which the ladder 2 is pivoted at B. A telescoping ladder-section 15 is pivoted to ladder-section 14 at A, and ladder 2 at C.

The device of Figure 4, as so far described, operates exactly like the devices of Figures 1, 2 and 3, the section 15 of Figure 4 corresponding to the dumbbell 8 of Figures 1 to 3, except that in Figure 4 the slippage is taken up in the telescoping member 15, and hence the angle at point B between ladder 2 and ladder-section 14 is distributed exactly equally over the two joints at A and C respectively.

Slidably carried by the telescoping section 15, as symbolically illustrated by brackets 16 bolted to the telescoping member 15 and bearing against the dumbbell about to be mentioned, is a telescoping dumbbell 17, similar to the dumbbell 8 of the other figures, except that it has a longer central portion and is telescoping.

A pipe 11 carried by the hull 1 is jointed to dumbbell 17 by a dumbbell 18, in exactly the same manner that the dumbbell 8 of the other two figures joins the pipes 11 and 5. Secured to the ladder 2 as at 19 and 20 is a pipe 5. A dumbbell 21 joins this pipe to the dumbbell 17 in exactly the same manner that dumbbell 8 in the other figures joins pipes 5 and 11.

The result is that the angle at point C, between the ladder 2 and the telescoping section 15, is distributed substantially equally over the ball joints between pipes 5 and dumbbell 21, and dumbbell 21 and dumbbell 17, respectively. Similarly the angle at point A, between the telescoping section 15 and ladder-section 14, is distributed substantially equally over the ball joints between dumbbell 17 and dumbbell 18, and dumbbell 18 and pipe 11, respectively. Thus

the angle at point B is distributed into four substantially equal parts each occurring at one of the four ball joints of Figure 4.

This principle of substantially equal division of an angle can be extended indefinitely by powers of two.

Although the foregoing exemplifies only one embodiment of our invention, we do not intend to limit ourselves to the particular disclosure, but intend to avail ourselves of all equivalents.

We claim:

1. In a hydraulic dredge, the combination of: a hull; a digging ladder, pivotally attached to the hull; a pipe, rigidly secured to the hull; a pipe, carried by the ladder, and slidably lengthwise thereof, but constrained against lateral movement with respect thereto; an intermediate section of pipe; two ball-and-socket pipe-joints, each of which joins the intermediate section to one or the other pipe; an additional pipe, rigidly secured to the ladder; and a slip-joint between this pipe and the slidable pipe; said slip-joint being so located as to lie below the water-level when the ladder is in its digging position; the pivot between the hull and the ladder and the pivots of the two ball-and-socket joints being so positioned that, in one position of the ladder, the three pivot points lie in a straight line, with the ladder-hull pivot lying substantially equidistant between the other two pivot points.

2. In a hydraulic dredge, the combination of: a hull; a digging ladder, pivotally attached to the hull; a pipe, rigidly secured to the hull; a pipe, carried by the ladder, and slidably lengthwise thereof, but constrained against lateral movement with respect thereto; an intermediate section of pipe; two ball-and-socket pipe-joints, each of which joins the intermediate section to one or the other pipe; an additional pipe, rigidly secured to the ladder; and a slip-joint between this pipe and the slidable pipe; the pivot between the hull and the ladder and the pivots of the two ball-and-socket joints being so positioned that, in one position of the ladder, the three pivot points lie in a straight line, with the ladder-hull pivot lying substantially equidistant between the other two pivot points.

3. In a hydraulic dredge, the combination of: a hull; a digging ladder, pivotally attached to the hull; a pipe, rigidly secured to the hull; a pipe carried by the ladder, and slidably lengthwise thereof, but constrained against lateral movement with respect thereto; an intermediate section of pipe; and two ball-and-socket pipe-joints, each of which joins the intermediate section to one or the other pipe; the pivot between the hull and the ladder and the pivots of the two ball-and-socket joints being so positioned that, in one position of the ladder, the three pivot points lie in a straight line, with the ladder-hull pivot lying substantially equidistant between the other two pivot points.

pivot lying substantially equidistant between the other two pivot points.

4. In a hydraulic dredge, the combination of: a hull; a digging ladder, pivotally attached to the hull; a pipe, rigidly secured to the hull; a pipe, carried by the ladder, and slidably lengthwise thereof, but constrained against lateral movement with respect thereto; an intermediate section of pipe; and two ball-and-socket pipe-joints, each of which joins the intermediate section to one or the other pipe; the pivot between the hull and the ladder and the pivots of the two ball-and-socket joints being so positioned that, in the mean position of the ladder, the three pivot points lie in a straight line, with the ladder-hull pivot lying substantially equidistant between the other two pivot points.

5. A flexible pipe-coupling, comprising in combination: a structure; a supporting element, pivoted thereto to rotate about a fixed axis; a pipe, fixedly carried by the structure; a pipe, slidably carried by the supporting element; an intermediate connecting pipe, having at each end a hinged connection with an end of one of said pipes, the axes of both hinged connections being parallel to the first-mentioned axis; and a fourth pipe, fixedly carried by the supporting element, and slidably jointed to the pipe which is slidably carried by the supporting element; the axis between the structure and the supporting element lying, in one position of the device, midway between the axes of the two hinged connections.

6. A flexible pipe-coupling, comprising in combination: a structure; a supporting element, pivoted thereto to rotate about a fixed axis; a pipe, fixedly carried by the structure; a pipe, slidably carried by the supporting element; and an intermediate connecting pipe, having at each end a hinged connection with an end of one of said pipes, the axes of both hinged connections being parallel to the first-mentioned axis; the first-mentioned axis lying, in one position of the device, midway between the two axes of the hinged connections.

7. A flexible pipe-coupling, comprising in combination: a structure; a supporting element, pivoted thereto; a pipe, fixedly carried by the structure; a pipe, slidably carried by the supporting element; an intermediate connecting pipe, having at each end a universal joint connection with an end of one of said pipes; and a fourth pipe, fixedly carried by the supporting element, and slidably jointed to the pipe which is slidably carried by the supporting element; the pivot point between the structure and the supporting element lying, in one position of the device, midway between the pivot points of the two universal joints.

8. A flexible pipe-coupling, comprising in combination: a structure; a supporting ele-

ment, pivoted thereto; a pipe, fixedly carried by the structure; a pipe, slidably carried by the supporting element; and an intermediate connecting pipe, having at each end a universal joint connection with an end of one of said pipes; the pivot point between the structure and the supporting element lying, in one position of the device, midway between the pivot points of the two universal joints.

9. A flexible pipe-coupling, comprising in combination: a structure; a supporting element, pivoted thereto; a pipe carried by the structure; a pipe, carried by the supporting element; and an intermediate connecting pipe, having at each end a universal joint connection with an end of one of said pipes; the pivot point between the structure and the supporting element lying, in one position of the device, midway between the pivot points of the two universal joints; and one of said three pipe-elements being provided with a slip-joint, to take up the necessary relative longitudinal travel between the parts of the device.

10. The combination of: two rigid, pivotally connected members; two pipes, each carried by one or the other member and constrained against lateral movement with respect to its member; an intermediate section of pipe; and two ball-and-socket pipe-joints, each of which joins the intermediate section to one or the other pipe; the pivot between the two members and the pivots of the respective ball-and-socket joints being so positioned that, in one relative position of the two members, the three pivot points lie in a straight line, with the pivot of the two members lying substantially equidistant between the other two pivot points.

11. The combination of: two rigid pivotally connected members; two pipes, each carried by one or the other member and constrained against lateral movement with respect to its member; an intermediate section of pipe; and two ball-and-socket pipe-joints, each of which joins the intermediate section to one or the other pipe; the pivot between the two members and the pivots of the respective ball-and-socket joints being so positioned that, in the mean relative position of the two members, the three pivot points lie in a straight line, with the pivot of the two members lying substantially equidistant between the other two pivot points.

12. A mechanical movement, comprising in combination: a first rigid element; a second rigid element, pivoted thereto; a third rigid element, rigidly held by the first; a fourth rigid element, carried by the second and constrained against lateral movement with respect thereto; and a fifth rigid element, which is pivoted to the third element, and which is pivoted to the fourth element; the elements being so located and disposed that,

in one position of the device, the pivot joining the first and second elements lies substantially midway between the pivot joining the third and fifth elements and the pivot joining the fourth and fifth elements.

5 13. A flexible pipe-coupling, comprising in combination: two pipe-ends; an intermediate connecting pipe, having a ball-and-socket joint connection with each of the pipe-ends; and means whereby these two joints are restrained from turning otherwise than about parallel axes, and means whereby the angle between the two pipe-ends is distributed substantially equally between the two angles, each of which is formed by one pipe-end and the intermediate connecting pipe.

10 14. As a new article of manufacture, a flexible pipe-coupling, comprising two pipe-ends, an intermediate rigid connecting pipe, and jointed carrying means, the whole being so arranged that the angle between the two pipe-ends is distributed substantially equally between the two angles, each of which is formed by one pipe-end and the intermediate rigid

15 connecting pipe.

20 15. As a new article of manufacture, a pivotally flexible pipe-juncture, comprising an intermediate pipe section and two extreme pipe sections, the intermediate section being swivelly jointed to each of the two extreme sections; means for carrying each of the extreme pipe sections; and a pivot between these two means, said pivot being located substantially opposite the middle of the intermediate pipe section.

25 16. As a new article of manufacture, a pivotally flexible pipe-juncture, comprising an intermediate section and two extreme sections of pipe jointed together, the joints being internally flared ball-and-socket joints; means for carrying each of the extreme pipe sections; and a pivot between these two means, said pivot being located substantially opposite the middle of the intermediate pipe section.

30 45 In testimony whereof we affix our signatures.
